UNITED STATES PATENT OFFICE.

ADOLPH H. SMITH AND GEORGE W. NIBBE, OF CHICAGO, ILLINOIS.

RAIL-ANCHOR.

1,139,816.

Specification of Letters Patent. Patented May 18, 1915.

Application filed August 26, 1914. Serial No. 858,645.

To all whom it may concern:

Be it known that we, ADOLPH H. SMITH and GEORGE W. NIBBE, citizens of the United States, residing at Chicago, in the county of Cook and State of Illinois, have invented 5 certain new and useful Improvements in Rail-Anchors, of which the following is a specification.

Our invention relates in general to railway track fastening devices, and more particularly to rail anti-creepers. It is well known that the passage of trains over railway tracks tends to shift the tracks longitudinally in the direction of the movement 10 of the trains. When the trains run in opposite directions on the same tracks the tendency of the tracks to creep in one direction is compensated by their tendency to creep in the opposite direction, but when the trains 15 run only in one direction, as is the case with double track roads, the creeping or shifting of the rails is so considerable as to be dangerous unless prevented.

The primary object of our invention is to 20 provide improved anchoring devices for railroad rails to prevent longitudinal creeping or shifting thereof, which will securely retain the rails against longitudinal movement relatively to the ties, and will be automatically actuated by any tendency of the rails 25 to creep to grip the rails more securely and effect a more rigid resistance to the creeping tendency.

A still further object of our invention is 30 to provide an improved anti-creeper for railroad rails which will be simple in construction, convenient in application, efficient in operation, and durable in use.

Our invention will be more fully disclosed 35 hereinafter with reference to the accompanying drawings, in which the same is illustrated in a convenient and practical form, and in which—

Figure 1 is an elevational view showing 40 our invention applied to a rail; Fig. 2 a perspective view of one of the clamping members; Fig. 3 a perspective view of the other clamping member; and Fig. 4 a plan view looking upwardly with respect to Fig. 45 1, showing the engagement of the clamping members beneath the rail base.

Reference letter A indicates a railroad rail, the base *a* of which is supported upon a tie *B*.

50 C and D designate interlocking clamping members which are adapted to be secured

to the base of the rail adjacent the tie *B* and to engage the tie to prevent the creeping of the rail toward the same. The clamping members C and D are provided with upwardly and inwardly extending flanges *c* and *d*, respectively, which are adapted to engage the opposite sides of the base *a* of the rail. The clamping members are provided with portions which transversely overlap beneath the rail base, and at the inner edges of such transversely overlapping portions are provided longitudinally overlapping parts G and H. The transversely overlapping portions of the clamping members 65 C and D are cut away, as shown at *e* and *f*, respectively, in order that such transversely overlapping portions may also longitudinally overlap to permit the depending longitudinally overlapped portions G and H 70 to be longitudinally adjusted with relation to each other to the requisite degree to effect the gripping of the edges of the rail base by the flanges *c* and *d* of the clamping members. It will be observed by reference to 75 Fig. 4 that the vertical contacting faces of the longitudinal overlapping parts G and H meet in a longitudinal plane slightly inclined from the longitudinal plane of the rail, in order that when said parts are relatively moved longitudinally into interlocked engagement, the clamping members will be drawn toward each other and thereby securely grip the rail base.

The contacting vertical surfaces of the 80 longitudinal overlapping parts G and H are preferably serrated, as indicated at *g* and *h*, in order that the clamping members may be positively retained in the adjusted positions 85 to which they may be forced in securing 90 them tightly to the rail base.

One of the clamping members, as for instance D, is provided with a depending shoulder *K*, which bears against the adjacent surface of the tie *B* so that any tendency of the rail to creep toward the tie tends to move the clamping member C with it and relatively to the clamping member D owing to the latter being retained against such longitudinal movement by reason of the bearing of its shoulder *K* against the tie. Therefore, any tendency of the rail to creep toward the tie effects a more secure gripping of the clamping members with the rail base 100 and consequently a more secure anchoring of 105 the rail with respect to the tie.

When the clamping members are in in-

terlocked engagement it will be seen that the end of the depending part H extends beneath the overlying portion E of the clamping member C, and also that the end of the 5 depending part G extends beneath the overlying portion F of the complemental clamping member D.

Our improved anti-creeping device may be readily applied to a rail by engaging the 10 clamping members with the rail base, the clamping member D being located adjacent the tie B and with the shoulder K thereon bearing against the adjacent vertical surface of the tie. The depending parts G and 15 H are placed in longitudinally overlapped relation with their ends respectively underlying the portions E and F of the respective clamping members. The member C is then driven toward the tie so that the relative longitudinal movement of the depending parts G and H will, owing to the inclination of the plane of their contacting surfaces to the longitudinal plane of the rail, draw the flanges c and d into tightly gripping relation with the rail base. 20 25

From the foregoing description it will be observed that we have invented an improved anchoring device for preventing the creeping or shifting of railroad rails relatively to the ties, which comprises two 30 clamping members having transversely and longitudinally overlapping portions located beneath the base of the rail and so related as to secure the rigid gripping of the clamping members upon the rail base and the consequent anchoring of the rail against any movement toward the tie with which one of 35 the clamping members engages.

What we claim is:

1. The combination with a railroad rail and supporting tie therefor, of a pair of 40 clamping members engaging the opposite sides of the rail base comprising transversely overlapping portions extending beneath the rail base, the ends of said overlapping portions having interlocking depending wedge elements. 45

2. The combination with a railroad rail and supporting tie therefor, of a pair of 50 clamping members engaging the opposite sides of the rail base comprising transversely overlapping portions extending beneath the rail base, the ends of said overlapping portions having interlocking depending wedge elements, and the said overlapping 55 portions being cut away to permit the relative longitudinal adjustment of said wedge elements.

3. The combination with a railroad rail

and supporting tie therefor, of a pair of 60 clamping members engaging the opposite sides of the rail base comprising transversely overlapping portions extending beneath the rail base, the ends of said overlapping portions having interlocking depending wedge elements, the end of each of 65 said wedge elements extending beneath the transversely overlapping portion of the other member.

4. The combination with a railroad rail 70 and supporting tie therefor, of a pair of clamping members engaging the opposite sides of the rail base comprising transversely overlapping portions extending beneath the rail base, the ends of said overlapping portions having interlocking wedge elements, each of said members having a chamber to receive the end of the wedge element of the other member so as to permit the relative longitudinal adjustment of the 75 80 wedge elements.

5. The combination with a railroad rail and supporting tie therefor, of a pair of 85 clamping members engaging the opposite sides of the rail base comprising transversely overlapping portions extending beneath the rail base, the ends of said overlapping portions having interlocking wedge elements, the vertical contacting surfaces of which are 90 provided with serrations.

6. In a device for preventing the creeping of railroad rails, a clamping member comprising a flange to engage the rail base, a portion to extend beneath the rail base, and a depending wedge element having serrations on the vertical surface thereof to engage corresponding serrations on a similar wedge element of a coöperating clamping member. 95

7. In a device for preventing the creeping 100 of railroads rails, a clamping member comprising a flange to engage the rail base, a portion to extend beneath the rail base, and a depending wedge element at the wedge of 105 said portion having serrations on the vertical surface thereof to engage corresponding serrations on a similar wedge element of a coöperating clamping member, said portion being cut away to permit longitudinal 110 adjustment of the clamping member relatively to the coöperating clamping member.

In testimony whereof, we have subscribed our names.

ADOLPH H. SMITH.
GEORGE W. NIBBE.
